UNITED STATES PATENT OFFICE.

GEORGE W. CAMPBELL, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed August 20, 1920. Serial No. 404,890.

To all whom it may concern:

Be it known that I, GEORGE W. CAMPBELL, a citizen of the United States, residing in Hartford, in the county of Hartford and 5 State of Connecticut, have invented certain new and useful Improvements in Typewriting Machines, of which the following is a specification.

This invention relates to line-spacing 10 mechanism for typewriting machines, and its object is to produce a light, simple and durable mechanism, so that it may be used with a portable typewriting machine.

Other features and advantages will here- 15 inafter appear.

In the accompanying drawings,

Figure 1 is a top plan view of the left- 20 hand end of a carriage of an Underwood portable typewriting machine, showing the invention applied thereto.

Figure 2 is a front elevation, partly in section, of the parts shown in Figure 1.

Figure 3 is a sectional side view, showing the left-hand end of the carriage, the 25 line-spacing mechanism being set to effect double line-spacing movements of the platen. A line-space detent, which is in its ineffect- tive position, is also shown.

Figure 4 is a perspective view, as seen 30 from the upper left-hand corner and from the front of the machine, of the line-spacing mechanism.

Figure 5 is a view similar to Figure 3, and shows the line-spacing mechanism set 35 to effect a single line-space movement of the platen.

Figure 6 is a side view of the detent throw- 40 off lever, and shows the position which it normally bears relatively to the line-space detent.

The line-space lever 10, having a finger- 45 piece 11, may be swung rightwardly (Fig- ures 1 and 4) about a pivot stud 12, to draw a line-space pawl 13 rearwardly by means of an arm 14 of the line-space lever 10; the 50 pawl 13 being in the form of a slide and pivotally connected to the arm 14 by means of a shouldered screw 15 threaded into said arm. The pawl 13 may be provided with a tooth 16, which may be formed on one side 55 thereof to engage a line-space wheel 17 se- cured to a platen axle or shaft 18 to rotate a platen 20, the tooth 16 being normally out of engagement with the line-space wheel 17. A return spring 21 may be connected

between a fixed stud 22 on a left-hand end plate 23 of a platen frame 24 and an ear 25 on the arm 14, to return the line-space lever 10 and the pawl 13. To facilitate ready assemblage, the pivot stud 12 for the 60 line-space lever 10 may comprise a shank 27 which is received in an opening 28 of a lug 30 secured to the left-hand end plate 23. The stud 12 may be held in position by means of a set-screw 31.

By an inspection of Figures 3 and 5, it will be seen that the line-space pawl 13 is provided with a nose 32 to bear against an extension 33 of the end plate 23, said ex- 70 tension serving as a stop to arrest the pawl 13 in its normal position. To arrest the rearward movement of the line-space pawl, there is provided a stop 34 projecting from the end plate 23 into a slot 35 in the line- 75 space pawl; the forward end 36 of the slot 75 engaging the stop when the line-space pawl is operated.

The lower edge of the slot 35 in the line- 80 space pawl 13, when the latter is operated, is brought close to the lower side of the stop 34, there being sufficient clearance to allow a slight upward movement of the pawl over a tooth of the line-space wheel 17 when the pawl is returning to its normal 85 position. Rotation of the platen, while the line-space pawl is in its operated position, is prevented, due to the fact that the tooth 90 of the line-space wheel 17 under the tooth 16 of the line-space pawl has a tendency to swing the line-space pawl upwardly, and this upward movement is checked by the stop 34; consequently, overthrow of the platen at the end of a line-space operation 95 is prevented.

One or more line-space movements of the 100 platen may be effected by setting the free end of the line-space pawl towards and away from the line-space wheel which has its teeth formed on its periphery, so that the tooth 16 may engage the line-space wheel sooner or later when operated by the line-space lever 10. To set the pawl, there is provided a line- 105 space controlling element 37 pivotally mounted on the platen-shaft 18. The con- trolling element or regulator 37 is provided with a finger-piece 38 projecting laterally through a slot 40 in the end plate 23, so that the controlling element may be operated. The line-space regulator is also provided 110 with a forked upward extension 41 having a

slot 42 therein to guide the line-space pawl 13 in its movement back and forth. The line-space pawl 13 is provided at its lower end with an uninterrupted guiding surface 43 to rest upon a shoulder 44 at the lower end of the slot 42 and to guide the pawl or slide 13 for substantially tangential movement relatively to the line-space ratchet-wheel 17, to or from the normal position of 5 the pawl or slide. The shoulder 44 is so shaped that when the line-space regulator 37 is set to the position indicated in Figure 5, a single line-space movement of the platen may be effected. When the regulator is set 10 to the position indicated in Figure 3, the forward end of the line-space pawl 13 is lowered, so that the tooth 16 thercon may engage the line-space wheel 17 one tooth space sooner than in Figure 5, so that the 15 platen may be rotated through two line-space distances when the line-space lever is operated. A spring 45 may be connected between the line-space pawl 13 and the lower end of the shouldered screw 15 (Figure 3) 20 to urge the tooth 16 of the line-space pawl toward the line-space wheel 17, thus preventing the pawl from accidentally disengaging the line-space wheel during line-spacing operations. A detent spring 46 may be 25 provided to hold the line space regulator 37 in its various positions. Said detent spring may be suitably secured to a cross-plate or tie-bar 48 (Figure 5) connecting the left-hand end plate 23 with the right-hand end 30 plate (not shown).

A detent 50 is provided to co-operate with the line-space wheel 17 to justify the platen when line-spaced. The detent may comprise a wheel or roller 51 which is normally 35 held against said line-space wheel, as in Figure 5, and is rotatably supported on a stud 52 between ears 53 of a flat spring 54 secured to a cross-bar 55 extending between the end plates of the platen frame 24. The 40 line-space detent 50 may be thrown to its ineffective position (Figure 3) by a detent-release lever 56 pivoted by means of a stud 57 on the end plate 23. The detent-release lever 56 is provided with a cam 56^a (Figure 45 6) which, when the lever is moved upwardly by a finger-piece 58, engages the stud 52 to move the detent wheel 51 to its ineffective position (Figure 3). The stud 52 snaps into a notch or cut-out 60 (Figure 6), to maintain the detent-release lever in its operated 50 position, as shown in Figure 3.

Since the carriages in portable machines are light in construction, it will readily be understood that the tension of the usual 60 spring drum (not shown), which feeds the carriage during typing operation, is also light, and consequently, the carriage may be returned to the beginning of a writing line by the line-space lever 10 before the line-spacing of the platen actually takes place,

the line-spacing being delayed by the line-space detent 50. In other words, the line-spacing of the platen is effected after the carriage has been arrested at the beginning of the writing line. Sometimes, however, 70 it is desirable to line-space the platen without restoring it to the beginning of a writing line. To this end, there is provided a fixed finger-piece 61 on the left-hand end plate 23. The finger-piece is located near, and 75 opposed to, the finger-piece 11 of the line-space lever 10, so that when the latter is engaged by the forefinger, the fixed finger-piece may be engaged by the thumb of the typist. The line-space lever 10 may then be 80 moved toward the fixed finger-piece 61 by a sort of pinching action of the fingers of the typist. Consequently, the rightward pressure on the finger-piece 11 of the line-space lever is equalized by the leftward 85 pressure on the fixed finger-piece 61, and the platen is line-spaced without returning it to the beginning of a writing line.

Variations may be resorted to within the scope of the invention, and portions of the 90 improvements may be used without others.

Having thus described my invention, I claim:

1. In a typewriting machine, the combination of a revoluble platen, a line-space 95 ratchet-wheel, operating means comprising a pawl to engage said line-space wheel to line-space the platen, and means comprising a regulator to swing said pawl to or away from the teeth of the line-space wheel, for 100 pointing said pawl to different teeth of the line-space wheel to vary the line-spacing of the platen, said regulator comprising a forked guide embracing the pawl to guide the pawl in its line-spacing movements. 105

2. In a typewriting machine, the combination of a revoluble platen, a line-space ratchet-wheel, a line-space lever, a substantially horizontally reciprocating slide connected at one end to said line-space lever, 110 the other end of said slide being free, a fixed tooth on the free end of said slide and normally disengaged from the line-space wheel, and means to raise or lower the free end of said slide to change the normal position of the tooth relatively to the line-space wheel to point said tooth to one or another of the teeth of the line-space wheel, to vary the line-spacing of the platen, said means comprising a forked guide embracing said 115 slide for guiding it in its reciprocating movements.

3. In a typewriting machine, the combination of a carriage, a revoluble platen on said carriage, a line-space ratchet-wheel on 125 said platen, a line-space lever pivoted at its rear end on said carriage, an arm on said lever at an angle thereto, a substantially horizontally movable slide connected to said arm, a tooth on said slide to engage said 130

line-space wheel but normally disengaged therefrom, a spring connected to said arm and to said slide to urge said slide towards said line-space wheel, fixed stops to be engaged directly by said slide to limit the movement of said slide, and means to vary the normal position of said pawl, so that it may engage one or another of the teeth of the line-space wheel when actuated by the line-space lever, said means comprising a forked guide embracing said slide to guide said slide in its line-spacing movements.

4. The combination with a revoluble platen and a carriage therefor, of a lever mounted upon a vertical pivot on the carriage and extending forwardly from the carriage for returning the same to begin a new line of writing, an arm provided upon said lever at an angle thereto, a pawl extending from said arm and comprising a tooth, a platen-rotating ratchet-wheel engageable by said tooth, the latter being normally disengaged from the wheel, a guiding plate provided upon said pawl and extending transversely of the platen axle, a forked guide embracing said plate and mounted loosely upon the platen axle, and a finger-piece connected to said guide to rock it about said platen axle, the bottom of the slot in said forked guide forming a cam which, when rocked by said finger-piece, points said pawl tooth to a different tooth of said ratchet-wheel.

5. In a typewriting machine, the combination with a revoluble platen and a line-space ratchet-wheel therefor, of a line-spacing pawl arranged transversely to the axis of the line-space wheel and normally disengaged from the teeth of the latter, a slotted guide embracing the pawl for guiding it laterally, and for supporting the pawl, and a finger-piece for shifting said guide to point the pawl to one or another of the teeth of the line-space wheel, for varying the line-spacing of the platen.

6. In a typewriting machine, in combination, a platen-frame having an end plate, a revoluble platen, a platen axle journaled in said end plate, a line-space ratchet-wheel connected to the platen between the end thereof and said plate, a carriage-returning line-space lever mounted on a vertical pivot at the end of the platen-frame and having a pawl-operating arm extending towards the line-space wheel, a pawl pivotally connected at its rear end to said operating arm and at its forward end provided with a tooth normally disengaged from the line-space wheel, a rockable pawl-guiding member pivoted loosely upon the platen axle between the platen and said end plate of the platen-frame, said guiding member being slotted to embrace the pawl for guiding it laterally and also supporting it, the bottom of the slot in said pawl-guiding rockable member

forming a cam shiftable around the platen axle to cause said pawl to engage one or another of the teeth of the line-space wheel, to vary the line-spacing of the platen, and a finger-piece for rocking said rockable member, projecting to the outer side of said end plate of the platen-frame.

7. In a typewriting machine, the combination with a revoluble platen and a line-space ratchet-wheel therefor, of a line-spacing pawl arranged transversely to the axis of the line-space wheel and normally disengaged from the teeth of the latter, said pawl having an uninterrupted guiding surface to guide it for substantially tangential movement relative to the ratchet-wheel, to or from its normal position, a guide-member upon which said pawl may slide along said guiding surface substantially tangential to the ratchet-wheel, and a finger-piece for shifting said guide-member to point the pawl to one or to another of the teeth of the line-space wheel.

8. The combination with a revoluble platen and a carriage therefor, of a carriage-returning line-space lever mounted upon a vertical pivot on the carriage and extending forwardly from the carriage to form a finger-piece, an arm provided upon said lever at an angle thereto, a pawl connected to said arm and having a tooth, a platen-rotating ratchet-wheel engageable by said tooth, the latter being normally disengaged from said wheel, a platen axle, a guiding plate provided upon said pawl and extending transversely of the platen adjacent to the platen axle, said guiding plate having an uninterrupted guiding surface to guide the pawl for substantially tangential movement relatively to the ratchet-wheel, to or from its normal position, a forked guide-member embracing said plate and pivoted loosely upon the platen axle, and a finger-piece connected to said guide-member to rock it about the platen axle, the bottom of the slot in said forked guide-member forming a guide along which said pawl may slide upon said guiding surface substantially tangential to the ratchet-wheel, and the bottom of said slot also forming a cam which, when rocked by said finger-piece, points said pawl tooth to a different tooth of said ratchet-wheel.

9. The combination with a revoluble platen and a carriage therefor, of a lever mounted upon a vertical pivot on the carriage and extending forwardly from the carriage for returning the same to begin a new line of writing, an arm provided upon said lever at an angle thereto, a pawl extending from said arm and comprising a tooth, a platen-rotating ratchet-wheel engageable by said tooth, the latter being normally disengaged from the wheel, a platen axle, a guiding plate, provided upon said pawl

and extending transversely of the platen axle, a forked guide embracing said plate and mounted loosely upon the platen axle, a finger-piece connected to said guide to 5 rock it about said platen axle, the bottom of the slot in said forked guide forming a cam which, when rocked by said finger-piece, points said pawl tooth to a different tooth of said ratchet-wheel, a longitudinal 10 slot in said guiding plate on the pawl, and a stop-lug on the carriage entering the slot in the guiding plate to limit the throw of the pawl.

10. The combination with a revoluble 15 platen and a carriage therefor, of a lever mounted upon a vertical pivot on the carriage and extending forwardly from the carriage for returning the same to begin a new line of writing, an arm provided upon 20 said lever at an angle thereto, a pawl extending from said arm and comprising a

tooth, a platen-rotating ratchet-wheel engageable by said tooth, the latter being normally disengaged from the wheel, a platen axle, a guiding plate provided upon said 25 pawl and extending transversely of the platen axle, a forked guide embracing said plate and mounted loosely upon the platen axle, a finger-piece connected to said guide to rock it about said platen axle, the bottom 30 of the slot in said forked guide forming a cam which, when rocked by said finger-piece, points said pawl tooth to a different tooth of said ratchet-wheel, and a stop on the carriage engageable with the pawl to 35 limit its line-spacing throw, and to hold the pawl in engagement with the ratchet-wheel to prevent overthrow of the platen.

GEORGE W. CAMPBELL.
